UNITED STATES PATENT OFFICE.

WILLIAM E. SNEDIKER, OF CAMDEN, NEW JERSEY.

VISE.

SPECIFICATION forming part of Letters Patent No. 709,120, dated September 16, 1902.

Application filed January 21, 1902. Serial No. 90,615. (No model.)

To all whom it may concern:

Be it known that I, WILLIAM E. SNEDIKER, a citizen of the United States, residing at Ninth street, above Market street, Camden, in the county of Camden and State of New Jersey, have invented certain new and useful Improvements in Vises, of which the following is a specification.

My invention relates to improvements in vises and particularly to that class of vises in which the jaws of the vise are at all times parallel with each other.

The object of my invention is to construct a vise which can be quickly adjusted, which can be locked or unlocked by turning the handle less than a complete revolution, and which will not get out of order on account of the handle not being permitted to turn more than a revolution, thereby overcoming the difficulty experienced in the use of quick-adjusting vises by inexperienced operators, who would invariably turn the handle several times in one direction until the mechanism would be in such a position that it could not operate properly.

A further object of my invention is to lock the reciprocating screw-nut into engagement with the fixed toothed rack before the jaws of the vise are tightened, thus insuring the complete engagement of the teeth of the screw-nut and the toothed rack, thereby preventing the difficulty heretofore experienced in the teeth of the screw-nut and the teeth of the rack only partially engaging, and consequently stripping off the teeth and making the vise useless.

Referring to the drawings, Figure 1 represents a sectional view of a vise with the locking mechanism released. Fig. 2 is a sectional view taken on line 2 2, Fig. 1. Fig. 3 is a sectional view on line 3 3, Fig. 1. Fig. 4 is a partial longitudinal sectional view of the vise, showing the position of the parts when locked. Fig. 5 is a sectional view on line 5 5, Fig. 4, showing the parts in different position from Fig. 2. Fig. 6 is a sectional view on line 6 6, Fig. 4, showing the parts in different positions from Fig. 3.

A represents the movable jaw of the vise, which forms a part of the housing, consisting of the bed-plate *a*, the side webs *a' a'*, and the top *a²*, as clearly shown in Fig. 3, the bed-

plate being provided with suitable means for attachment to a bench or table.

B represents the movable jaw. On said jaw 55 is provided a bearing *b*, in which is mounted a shaft *E*. Said shaft is adapted to rotate in the opening *b'* of the bearing *b*. Said opening *b'* being slightly larger than the shaft *E* permits the inner end of said shaft to be raised 60 or lowered by means of the cams *F* and *G*, the bearing *b* forming a fulcrum for the same. As shown in Fig. 2, a lug *b³* is provided on the jaw *B*, against which the cam Facts. Said lug also acts as a stop, which prevents the projection *f* on the shaft *E* from turning further than desired. In the portion 65 C of the jaw *B* is provided a set-screw *H*. Said set-screw engages the cam *G* on the inner end of the shaft *E*, and when the cam is in 70 the position shown in Figs. 1 and 3 the inner end of the shaft *E* is allowed to be raised and held against said set-screw by the action of the cam *F* on the outer end of said shaft coming in contact with the lug *b³* on the jaw 75 *B*. Said set-screw is threaded and forms an adjustable bearing for the cam *G*; but a lug on the sliding portion *C* could be used without departing from my invention.

The shaft *E* is provided with a screw-thread 80 *e*, on which is mounted a screw-nut *I*. The lower face of said screw-nut is provided with teeth *i*, which engage with a rack *J*, having teeth *j* secured to the fixed bed-plate *a*.

In Fig. 1 the jaw *B* is released and can be 85 moved in or out to any desired position, as the sliding portion *C* is permitted to slide freely in the opening *D* in the jaw *A*, the screw-nut *I* on the shaft *E* being held out of engagement with the rack *J*. The position 90 of the cam *F* when the vise is released is shown in Fig. 2, the shaft *E* being turned as far to the left by means of the handle *K* as the projection *f* will permit. Fig. 3 shows the position of the cam *G* when the vise is released, as shown in Fig. 1. Fig. 4 shows the 95 jaws of the vise locked with an object *w* clamped between them. The shaft *E*, as shown in this view, has been turned slightly more than one-half of a revolution, the handle *K* being turned to the right, and, as shown in Fig. 5, the cam *F* has been moved away 100 from the projection *b³* on the jaw *B*, and, as shown in Fig. 6, the cam *G* on the inner end

of the shaft has been turned so as to depress said inner end of the shaft E and bring the screw-nut I in contact with the rack J, secured to the fixed bed-plate *a*. The cam G, as shown in Figs. 3 and 6, has a very small portion of its periphery cut away to form the low side of the cam, and a very slight rotation of the shaft E will cause said shaft to be depressed and force the screw-nut I down into engagement with the teeth of the rack J. The screw-nut I is depressed with such a slight rotation of the threaded shaft E that it moves downwardly in almost a vertical line, and as this is done before the jaws of the vise 15 tighten the screw-nut I will find a perfect seat on the toothed rack. Should the points of the teeth of the screw-nut and the rack strike each other, the cam G will force them together, causing a slight forward movement 20 of the movable jaw B, which space will be taken up when the shaft E is further rotated to tighten the jaws of the vise. When the teeth on the nut I come in complete engagement with the rack J, the screw-nut cannot 25 move longitudinally, and when the shaft continues to rotate the screw-thread on the same engaging with the screw-thread in the screw-nut I will have a tendency to draw the movable jaw B tightly against the object to be 30 clamped in the vise.

Having thus described my invention, I claim and desire to secure by Letters Patent—

1. The combination in a vise of the fixed 35 jaw and casing, a fixed rack, a movable jaw, a sliding portion on the same, a threaded shaft, a screw-nut to engage said rack, cams on said shaft adapted to raise and lower the inner end of said shaft substantially as de- 40 scribed.
2. The combination in a vise of the fixed

jaw and rack, a movable jaw, a threaded shaft, a screw-nut adapted to engage said rack, a cam on said shaft acting against the movable jaw to raise the inner end of said shaft, and a cam on the inner end of said shaft adapted to depress the inner end of said shaft substantially as described. 45

3. The combination in a vise of the fixed jaw and rack, a movable jaw, a threaded 50 shaft, a screw-nut, cams on said shaft to bring the screw-nut into or out of engagement with the fixed rack.

4. The combination in a vise of the fixed jaw and rack, a movable jaw, a threaded 55 shaft, a screw-nut, cams on said shaft to bring the screw-nut into or out of engagement with said rack, a set-screw on said movable jaw acting against the cam on the inner end of said shaft substantially as de- 60 scribed.

5. The combination in a vise of the fixed jaw and rack, a movable jaw, a threaded shaft, a screw-nut, cams on said shaft to bring the screw-nut into or out of engagement with said rack, a lug on the movable 65 jaw acting against the cam on the outer end of said shaft, substantially as described.

6. The combination in a vise of the fixed jaw and rack, a movable jaw, a threaded 70 shaft, a screw-nut, cams on said shaft to bring the screw-nut into or out of engagement with said rack, a projection on said shaft to prevent said shaft from turning, substantially as described. 75

In testimony whereof I have affixed my signature in presence of two witnesses.

WILLIAM E. SNEDIKER.
